(57) **CLAIM**

The ornamental design for a vehicle accessory attachment channel, as shown and described.

DESCRIPTION

FIG. 1 is a front perspective view of the vehicle accessory attachment channel;

FIG. 2 is a front elevation view of the vehicle accessory attachment channel of FIG. 1;

FIG. 3 is a rear elevation view of the vehicle accessory attachment channel of FIGS. 1 and 2;

FIG. 4 is right side elevation view of the vehicle accessory attachment channel of FIGS. 1-3;

FIG. 5 is a left side elevation view of the vehicle accessory attachment channel of FIGS. 1-4;

FIG. 6 is a top plan view of the vehicle accessory attachment channel of FIGS. 1-5;

FIG. 7 is a bottom plan view of the vehicle accessory attachment channel of FIGS. 1-6; and,

FIG. 8 is an enlarged front perspective view, taken along

circle 8 of FIG. 1.

The broken lines in the drawings illustrate portions of the vehicle accessory attachment channel and form no part of the claimed design. The dot-dash-dot broken lines in the drawings define the bounds of the claim and form no part thereof.

1 Claim, 6 Drawing Sheets
